CLAIM

The ornamental design for a dish storage rack, as shown and described.

DESCRIPTION

FIG. 1 is a first perspective view of a dish storage rack showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown, in the drawings depict portions of the dish storage rack that form no part of the claimed design.
